Primary Examiner — Brett Miller*Assistant Examiner* — Rani J Abdallah(74) Attorney, Agent, or Firm — Husch Blackwell LLP(57) CLAIM

I claim the ornamental design for a jar, as shown and described.

DESCRIPTION

FIG. 1 is a perspective view of a jar;

FIG. 2 is a front elevation view of the jar;

FIG. 3 is a right side elevation view of the jar;

FIG. 4 is a left side elevation view of the jar;

FIG. 5 is a rear elevation view of the jar;

FIG. 6 is a top plan view of the jar; and,

FIG. 7 is a bottom plan view of the jar.

Broken lines shown in the drawing views are included for illustrative purposes only and form no part of the claimed design.
